STORAGE VESSEL

Erwin G. Dueringer, Milwaukee, Wis., assignor to A. O. Smith Corporation, Milwaukee, Wis., a corporation of New York

Application February 19, 1953, Serial No. 337,701

1. Claim. (Cl. 189—3)

This invention relates to storage structures and more particularly to an air-tight corrosion resistant silo constructed of a plurality of helically wound glass-coated metal strips.

An object of the present invention is to provide an inexpensive corrosion-resistant silo which may be readily assembled in the field with a minimum of labor.

Another object of the invention is to provide a substantially air-tight silo having a minimum of bolted joints.

Still another object is to provide a silo constructed of several helically wound metal strips which substantially reduces the number of parts to be handled during shipment and erection of the silo.

Another object is to provide a strong supporting foundation for the silo whereby the foundation may be conveniently constructed by the former with a minimum of concrete.

In general the silo of the present invention comprises a generally cylindrical body section which is enclosed at the top by a generally curved roof and is supported at the bottom by a concrete foundation. The body section consists of a plurality of glass-coated steel sheets or strips which are successively wound in helical or spiral form. The trailing end of each strip is secured along a vertical line to the leading end of the following strip. The helical or side edges of the strips are overlapped and secured together with the upper side edge of each lower convolution overlapping the lower side edge of the preceding upper convolution to provide an interior surface in which each lower convolution is outwardly offset so as not to obstruct the downward movement of the contained material. Each of the sheets is constructed with a predetermined thickness to withstand the internal pressure of the stored material at the level at which the sheet is disposed.

In addition the silo is provided with a suitable internal supporting structure which carries a rotating cutter arm to undercut the silage and a conveyor unit to transport the cut silage to the exterior of the silo. The silo is also provided with a suitable door or manway which registers with the conveyor unit to effect the removal of the contained material.

In the drawings:

Figure 1 is a perspective view of a completed silo;

Fig. 2 is an enlarged fragmentary perspective view of the silo with parts broken away to show the internal supporting structure;

Fig. 3 is a fragmentary vertical section of the silo showing the position of the mechanical unloading apparatus;

Fig. 4 is a horizontal section taken along line 4—4 of Fig. 3;

Fig. 5 is a fragmentary transverse section taken along line 5—5 of Fig. 4 and showing the unloading trough;

Fig. 6 is a plan view of a sheet with parts broken away and showing how the tapered end portions of the upper-

2

most and lowermost strip are formed from a single strip; and

Fig. 7 is a plan view of one of the intermediate strips with a part broken away.

5 Referring to the drawings there is shown a generally cylindrical silo 1 or the like which is enclosed at the top by a generally conical roof 2 and supported at the bottom by an annular concrete footing 3.

Silo 1 consists of a plurality of strips 4 or sheets of metal which are successively wound in a helical manner. Strips 4 are preferably constructed of steel coated with glass, plastic or a similar corrosion resistant material or they may be made of a suitable corrosion resistant alloy.

The strips are each constructed with a predetermined 15 thickness to withstand the internal pressure of the contained material at the particular position where each strip is located. For example, in a silo having a diameter of about twenty feet, the uppermost of the strips 4 is the longest of the four strips and is constructed with

20 a thickness in the neighborhood of one-sixteenth of an inch. The following or intermediate strip has a slightly greater thickness, approximately three thirty-seconds of an inch, and the intermediate strip is followed in turn by the grade strip which has the greatest thickness of the

25 four strips, such as one-eighth of an inch. As the grade strip extends downwardly to slightly below grade level it is subjected to an internal pressure exerted by the entire weight of the contained material, and to withstand this pressure the grade strip is designed with a greater thickness than the other strips.

The lowermost of strips 4 is attached to the grade strip and extends downwardly therefrom in a helical manner to footing 3. As the lowermost strip is not subjected to the pressure of the contained material, as will be herein-after shown, it is designed with a minimum thickness approximating the thickness of the uppermost strip; namely, about one-sixteenth of an inch.

In order that the circular lower edge of silo 1 lies in a horizontal plane and that the silo be vertically disposed 40 when resting on footing 3, the trailing end of the lowermost of the strips 4 is tapered to a point-like tip as indicated by 5.

Similarly the leading end of the uppermost of the strips 4 is tapered to a pointed tip 6 so that the upper circular edge of silo 1 also lies in a substantially horizontal plane. Fig. 6 shows how the uppermost strip and the lowermost strip may be cut from a single long strip to give the properly tapered tips 5 and 6.

As there shown the trailing and leading ends of each 50 of the strips 4, with the exception of the aforementioned trailing end of the lowermost strip and the leading end of the uppermost strip, are cut on the helix angle, to obtain a vertical joint when the trailing end of one strip is secured in a lapping relation to the leading end of the following strip. A plurality of spaced smooth-head bolts 7 are employed to secure the lapped ends of strips 4 together. The bolts are inserted from the interior of the silo through aligned holes in the vertical lapped ends of the respective strips and are engaged on the 55 outside of the silo by suitable nuts.

The strips 4 are wound in a helical manner from the top down with the upper side edge of each successive convolution overlapping the lower side edge of the preceding convolution so that each lower convolution is 60 offset outwardly to provide an internal silo surface which will not obstruct the downward movement of silage or similar contained material.

To attach the overlapping helical side edges of strips 4 together to form the cylindrical body portion of the silo 70 a plurality of spaced smooth-head bolts 8 are inserted from the interior of silo 1 through suitable aligned holes in the lapped side edges of strips 4 and are en-

gaged on the exterior of the silo by suitable nuts. The bolt holes in the overlapped portion of each strip adjacent the lower side edges thereof are uniformly spaced and equidistant in all strips.

However, the bolt holes in the overlapping portion of each strip, adjacent the upper side edge thereof, are not uniformly spaced, but instead are positioned in alignment with the holes adjacent the lower side edges of the preceding convolution and thus the spacing of holes adjacent the upper side edges of strips 4 must compensate for the overlap of convolutions and the varying thicknesses of the strips.

To prevent leakage of silage juices or the like through the vertical or helical joints, a mastic or other sealing material may be disposed between the lapped edges prior to the securement thereof by the bolts 7 and 8.

Roof 2 is formed of a number of pie-shaped segments with flange extremities to provide an annular flange that extends over the top circular edge of silo 1 and which is secured thereto. A suitable opening is provided in roof 2 through which the silage or the like is introduced into the silo. To maintain the air-tight properties of the silo the opening is closed by a removable cover 9 when not in use.

Footing 3, as seen in Fig. 2, which supports silo 1 is generally annular in shape and is constructed of concrete or the like. Footing 3 is disposed beneath the exterior grade level of the structure with the distance beneath grade level depending on the frost penetration in the particular area where the structure is to be erected.

A base angle ring 10 rests on footing 3 and is secured by suitable bolts to the inner bottom edge of silo 1. Ring 10 may be constructed of a number of arcuate segments which are individually bolted to the silo. A plurality of circularly spaced anchor bolts 11 are embedded in footing 3 and project upwardly therefrom.

A clamp plate 12 cooperates with each bolt 11 to attach base angle ring 10 to the footing 3. The outer extremity of each clamp 12 rests on the horizontal flange of angle ring 10 and the upwardly projecting end of the corresponding bolt 11 extends through an opening in the clamp 12 and is engaged by a suitable nut to secure the angle ring 10 to the footing 3. To maintain each clamp 12 in a substantially horizontal position and insure uniform pressure on angle ring 10, each clamp is provided with a downwardly bent inner end which rests on footing 3.

A generally cylindrical skirt ring 13 is concentric with and inwardly spaced from the cylindrical wall of silo 1 and rests on footing 3. Ring 13 extends upwardly from footing 3 to the interior grade level of the structure which is a slight distance above the exterior grade level.

Ring 13 is formed of a plurality of arcuate skirt sections 14. Each skirt section 14 is provided with a pair of vertical side flanges 15 and an inwardly extending top flange 16. Suitable bolts are employed to attach the side flanges 15 of adjacent skirt sections together to form the cylindrical skirt ring 13.

Skirt ring 13 is utilized to support an annular plate 17 which serves as a track for the outer extremity of a rotating cutter arm. The outer circular edge of plate or track 17 is secured by means of an angle ring 18 to the inner surface of silo 1, and the inner circular edge of track 17 is secured to the upper flange 16 of skirt sections 14. Track 17 is provided with suitable openings 19 or poke holes through which concrete may be poured into the annular space between the silo 1 and skirt ring 13 as a final step in the erection of the structure. To facilitate shipment and handling the track 17 may consist of a plurality of arcuate segments.

To provide a trough wherein the cut silage may be conveyed to the exterior of the silo a pair of spaced parallel channel members 20 extend diametrically across silo 1 and are secured at the ends thereof to the underside of track 17. The skirt sections 14 adjacent the channels 20

are reduced in height to permit the channels to extend outwardly of ring 13 and be secured to the underside of the track 17.

A generally semi-circular flanged plate 21 connects the spaced channels at the center of silo 1. Channels 20 and plate 21 carry a flat trough plate 22 which extends outwardly from the center of the silo in the direction of the open side of plate 21 to the skirt ring 13. Plate 22 is secured to the lower flange of each of the channels 20, to the lower edge of plate 21 and to the upper flange 16 of the front reduced portion of skirt 13. A trough 23 is thereby defined by channels 20, plate 21 and plate 22.

The space between silo 1 and skirt ring 13 contains concrete 24 or the like which is poured through poke holes 19 in track 17. Concrete 24 takes the shape of an annular wall and serves to generally reinforce and strengthen the structure.

To remove the cut silage from the silo, the silo is provided with a manway or unloading opening 25 which registers with trough 23. Suitable channel members 26 are secured about the opening 25 to strengthen the same and provide a smooth-edged generally rectangular entry. A suitable cover, may be employed to close off opening 25 and maintain the air-tight properties of the structure when the silage is not being removed.

The mechanical cutting and unloading apparatus, shown schematically, used to cut and remove the silage from the structure may correspond to that disclosed in the co-pending application of Julius B. Tiedemann, Serial No. 98,794, now Patent No. 2,635,770, entitled, "Method of Unloading Stored Material and Apparatus Therefor." The apparatus comprises a rotating cutter arm 27 with the outer end of the arm adapted to ride on track 17 to undercut and discharge the silage into trough 23 at the central portion of the silo. A conveyor unit 28 operating in trough 23 conveys the silage through opening 25 to the exterior of the silo.

The central area within silo 1 encircled by the skirt ring 13 is adapted to contain ground fill 29 and the fill provides additional support for the channels 20 and plate 22.

To protect all the metal parts of the structure, in addition to strips 4, against corrosion from either the elements or the material contained within the structure the metal parts may be given a protective enamel or plastic coating.

The present silo with the use of the helical construction reduces the number of plates required to construct a silo, or storage vessel, of given dimensions. The use of fewer plates reduces the number of joints which results in a savings in sheet metal overlaps as well as a savings in bolts and mastic.

The ordinary metal silo is constructed from a number of rectangular steel plates which are individually squared, drilled, rolled to curvature and coated. Both in the field and in the shop a large proportion of the total labor is spent in the transporting and the repeated handling of the multiple parts. The use of several helical strips, as shown in the present invention, in place of the large number of rectangular plates overcomes this inefficiency and brings about a definite saving in labor of manufacture and handling.

Although the invention has been described as applied to the use of enamel or glass coated metal strips it is contemplated that other materials such as plastic may be employed in which event the strips would be secured together by means other than bolting.

Various embodiments of the invention may be employed within the scope of the following claim.

I claim:

A cylindrical, vertically disposed silo-like storage vessel comprising a body section having a single supporting 75 and containing wall, said wall being formed of a plural-

ity of strips of material helically wound in a series of partially overlapping convolutions, securement means extending through the overlapping convolutions to secure the strips together, sealing material disposed between the overlapping convolutions of said strips to form a substantially airtight wall for the vessel, said strips being of predetermined varying thicknesses to withstand the vessel load and the internal pressure of the stored material at the particular position at which each strip is disposed in the body section, a roof member enclosing the top of said body section, and a foundation member disposed beneath the body section to support the same and close off the bottom of the section with the said metal strips being wound around at least a portion of the foundation to enclose said portion of the foundation and pro-

vide the foundation as internal support for the body section of said vessel.
